UNITED STATES PATENT OFFICE.

CALHOUN L. KELLEY, OF KENNETT, MISSOURI, ASSIGNOR OF THREE-FOURTHS TO CHARLES O. HOFFMAN, JOEL P. TRIBBLE, AND VIRGIL MCKAY, OF SAME PLACE.

DESIGN FOR A STUMP-BURNER.

SPECIFICATION forming part of Design No. 28,986, dated July 5, 1898.

Application filed May 27, 1898. Serial No. 681,954. Term of patent 14 years.

To all whom it may concern:

Be it known that I, CALHOUN L. KELLEY, a citizen of the United States, residing at Kennett, in the county of Dunklin and State of Missouri, have invented and produced a new and original Design for Stump-Burners, of which the following is a specification.

My invention relates to a new design for stump-burners or devices used for destroying the stumps of trees in cleared land; and the essential feature consists in the novel configuration given thereto.

In the accompanying drawings, Figure 1 represents an elevation of a stump-burner constructed in accordance with my invention. Fig. 2 is a plan view of the same.

In the said drawings the reference-numeral 1 designates a stove consisting of a cylinder provided at its upper end with a number of

outwardly-extending triangular teeth 2, giving the same an ornamental appearance. At the lower end said cylinder is formed with a flange 3 and is also formed with a number of perforations 4.

The numeral 5 designates the door of the stove, and 6 a chimney having a number of outwardly-extending curved prongs or teeth 7.

What I claim is—

The design for a stump-burner substantially as herein shown and described. 30

In testimony whereof I have hereunto set my hand in presence of two subscribing witnesses.

CALHOUN L. KELLEY.
